WARP SLACKENER FOR LOOMS

Walter H. Wakefield, Worcester, Mass., assignor
to Crompton & Knowles Loom Works, Worcester,
Mass., a corporation of Massachusetts

Application December 14, 1936, Serial No. 115,713

10 Claims. (Cl. 139—20)

This invention relates to improvements in slackeners for warps of looms more particularly adaptable for use in looms which weave two separate webs connected at intervals by crossing warps.

In the manufacture of Venetian blinds it is customary to string the cross slats on tapes which are spaced a distance corresponding to the width of the slats and having extended between them supporting webs for the slats. The space between crossing webs will ordinarily bear a relation to the width of the slats and occur at regular intervals throughout the length of the double pick. Between cross webs the crossing warps are woven into the tapes and at such times are left off from their separate warp beams at a rate substantially equal to the letting off of the main warps. When the warps are to be crossed, however, there is a momentary extra feed to supply the length to extend from one web to the other.

The mechanisms heretofore proposed for the feeding of the crossing warps have either been abrupt in their action in relieving the tension on the crossing warps too quickly, or they have employed a multiplicity of parts rendering their manufacture expensive and entailing considerable attention for their maintenance. It is an important object of my present invention to provide simple means for slackening these warps at a rate proportional to the advance of the lay by a simple mechanism which is thereafter effective to move the crossing warp control or slackener bar back to its normal rearward position.

It is a further object of my present invention to employ a single actuator coupled with control mechanism therefor which will permit a quick warp slackening or advance feed on the slackener bar followed by a slow warp tightening return motion, both motions of the slackener bar being accomplished by the single actuator.

It is another object of my present invention to provide a control for the actuator which in addition to permitting the foregoing feed and return strokes of the slackener bar is also effective to permit a succession of idle strokes of the actuator to occur between successive crossings of the crossing warp.

It is a more particular object of my present invention to provide a cam moving ratchet actuated by a single pawl which in turn is controlled by a shield having three positions the first of which is neutral to permit the pawl to have idle motions with respect to the ratchet, the second of which permits the pawl to give a

relatively large feeding motion to the ratchet to effect forward motion of the slackener bar, and the third position of which permits the gradual return of the slackener bar by allowing a small part only of the stroke of the pawl to operate the ratchet.

Another object of my invention relates to control means for the shield to be exercised by a counter mechanism and operative when an indication is given by said mechanism to move the shield from the first to the second of the positions above described, thereby causing forward feed of the warp through a shield controlled by the counter mechanism. The counter thereafter permits the shield to move toward neutral position, this motion, however, not being complete due to a control exercised by the slackener bar and effective to permit the gradual return motion of itself by giving the shield the third of the previously described positions. The slackener bar acts as it approaches its rearmost or normal position to permit the shield to return to neutral position.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a vertical section through a loom having my invention applied thereto,

Fig. 2 is a diagrammatic view of one form of counter mechanism for positioning the controller for the actuator,

Fig. 3 is a plan view on an enlarged scale of the mechanism for actuating the cam which controls the slackener bar,

Figs. 4 and 5 are vertical sections on lines 4—4 and 5—5, respectively of Fig. 3, and

Figs. 6, 7 and 8 are diagrammatic views showing the successive position of the shield with respect to the stroke of the actuator pawl and corresponding to neutral, forward feed for the slackener bar, and gradual return of the slackener bar to rear position.

Referring to Fig. 1, I have shown a loom frame 10 having a breast beam 11 and a lay 12 moved back and forth by a connector 13 driven by a top shaft 14. The lay has mounted thereon upper and lower decks of positively moved shuttles 15 and 16, respectively, which by connections not shown but well understood are driven through upper and lower sheds 17 and 18, respectively, defined by the tape forming warps W and W', re-

spectively, which may be drawn in any approved manner from warp beams not shown and correspond to top and bottom tapes T and T', respectively.

- 5 The crossing warp C passes under and extends forwardly from a movable slackener bar 19 hung on arms 20 depending from and secured to a small cross shaft 21 suitably mounted on the rear part of the loom frame 10. The crossing 10 warp extends forwardly in two sheets C' and C² for the top and bottom sheds, respectively.

15 Mounted on the breast beam is a structure designated generally at A having a crossing warp 20 advancer 22 which at the proper time is inserted 20 between the top and bottom sheds and behind the crossings of the sheets C' and C², after which 25 said advancer is moved forwardly so that the point of crossing between the sheets of crossing warps may be somewhat in advance of the fells 30 of the top and bottom webs. The structure A of itself forms no part of my present invention and may if desired be substantially the same as that shown in prior Patent No. 2,025,866. As shown 35 in that patent the advancer has a forward motion derived from the lay and moves forwardly therefore by a motion which is substantially the same as or at least proportional to the advance motion of the lay. During the forward motion of the 40 advancer it is desirable to slacken the warp C to relieve the same of undue strains and provide the necessary length required for the crossing web.

45 The matter thus far described may be similar to structure set forth in the aforesaid patent and operates substantially as described therein and as briefly set forth hereinbefore.

50 In order to effect the necessary forward feeding of the crossing warps provision is made for advancing the slackener bar 19 and to accomplish this result the shaft 21 has secured thereto an arm 25 from which depends a rod 26 attached to a chain 27 extending around sheaves 28 and extending down to another rod 29 the lower end of 55 which is attached to a control lever 30 pivoted as at 31 to a cross girt 32 of the loom.

60 A roll 35 on the lever 30 is positioned for engagement with a controlling cam 36 secured to a stub shaft 37 turning in bearing 38 as shown in Fig. 3 and normally at rest. The cam is adapted 50 for rotation in a counter-clockwise direction as viewed in Fig. 1 and has a high dwell area 40 normally in engagement with the roll 35 and from which extends an incline 41 terminating in a low dwell 42 which is approximately 90° from the high dwell 40. The cam has another high dwell 43 55 connected to the low dwell 42 by means of a second incline 44 similar to but the reverse of incline 41. The right side of the cam is similar to the left hand side just described and it is to be understood that a half rotation of cam 36 corresponds to a complete cycle for the slackener bar.

65 When the parts are in the full line position shown in Fig. 1 the high dwell 40 operates to hold the slackener bar 19 in its rearmost position, but at the time of a crossing of warps c, the cam is given a one-quarter turn during which the roll 35 moves upwardly along the surface or incline 41 until it reaches the low dwell 42. This motion occurs while the lay is moving forwardly and is 70 accomplished by a single motion of the control mechanism for the cam to be described herein-after. Thereafter the cam is given step by step motions to depress the roll 35 gradually until said roll is in contact with the other high dwell 43, at 75 which time the cycle will be complete.

In carrying my present invention into effect I provide a three-position shield which is under two separate controls the first of which is exercised by the pattern mechanism and the second of which is derived from the slackener bar. The 5 shield is of greater length than the stroke of the pawl which it controls and is movable to two different feeding positions.

In carrying my invention more particularly into effect I provide a rod 50 pivoted as at 51 to 10 the lay which rocks around its axis 52. A pawl arm 53 is mounted loosely on shaft 37 and has a slot 48 in which is located a stud 49 at adjusted distance from shaft 37. The arm 53 is provided with a feed pawl 54 which is urged toward the 15 shaft 37 by a light spring 47. As the lay moves back and forth the pawl 54 will move around the shaft 37, being in rearmost position when the lay is on back center and moving forwardly with the lay as the latter advances. While I have shown 20 this particular means for actuating the pawl yet I do not wish to be limited thereto and it is to be understood that the proportions of the connections which drive the pawl are such that the latter is given approximately a 90° motion around 25 the shaft 37.

25 The actuator pawl 54 is controlled by a shield 60, also pivoted loosely on shaft 37. This shield is longer than the stroke of the pawl 54 and is normally held in the neutral position shown in Figs. 30 1 and 4 by means of a light spring 65 connected to the shield at one end and attached to fixed structure at the other end thereof. The spring tends normally to hold the shield to the left or in the position of Fig. 4 against a fixed but adjustable stop 66. When the shield is in normal position the pawl 54 is movable from position a to position b, Fig. 6, remaining in contact with the shield throughout its stroke.

35 Secured to the shaft 37 is a ratchet wheel 70 40 adapted for engagement with the pawl 54, and when turned causing motion of the previously described cam 36. The shield lies over the upper part of the ratchet wheel and ordinarily prevents actuation thereof by the pawl.

45 In order that the shield may be moved from its neutral position I provide a connection from the 50 neutral position I provide a connection from the counting mechanism shown in Fig. 2. This mechanism includes a counter chain 71 having a single counter ball 72 movable under a vibrator 55 lever 73. The latter carries a vibrator gear 74 attached to a connector 75 which in turn rocks a lever 76 pivoted at 77. A flexible connection 78 is attached to the lever 76 and is conveniently trained around sheaves 79 to be connected to an 60 arm 80 of the shield. The leverage is such that a rocking of lever 76 from one extreme position to the other will move the shield through approximately 90°.

65 In order that the shield may have a feeding position I provide a control therefor to be operated by the slackener bar. Accordingly, I pivot a lever 85 at 86 and use a spring 87 to turn the lever in a left hand direction as viewed in Fig. 1. An arm 88 bears against the rear of the slackener bar 65 while a fixed stop 89 limits rocking of the lever under action of spring 87 when the bar 19 moves forwardly, or to the left in Fig. 1. A rod 90 attached to the lever 85 extends down through a bearing 91 and normally lies above a stop 95 70 moving with the shield.

75 In operation, when the roll 72 arrives under 75 vibration 73 there follows a rocking of lever 76 to the dotted line position with resultant movement of the shield from the position of Fig. 6

to that of Fig. 7. This occurs just before the lay reaches back center position. The pawl, therefore, drops to engage the ratchet and on the following forward beat of the lay the ratchet 5 and cam are turned through about 90°, permitting the slackener bar to move forwardly with a slackening stroke under the pressure of warp c. The latter, therefore, feeds the required amount to permit the crossing of warps.

10 During the first part of the motion of bar 19 the lever 85 rocks to depress rod 90 into the path of stop 95. This does not interfere with the pawl movement. In this interval the vibrator is still raised, hence the shield is held back in the position of Fig. 8.

On the following back stroke of the lay and before the latter reaches rear position, counter roll 72 will allow lever 13 to fall and lever 16 will be returned to normal full line position of Fig. 2. 20 This action releases the shield and spring 65 turns it toward neutral position, but rod 90, being down, engages stop 95 to arrest the shield in the position of Fig. 8, where it will be seen that only a small part of the stroke of the pawl is effective 25 to turn the ratchet.

The slackener bar remains forward and the rod 90 depressed for several beats of the loom, during which the pawl effects a step-by-step turning of the cam to cause incline 44 to depress lever 38. 30 The slackener bar 19 is, therefore, given a slow gradual return or warp tightening motion to normal rear position.

As the bar approaches its rear position it will engage arm 88 of lever 85 to lift rod 90 away from the stop 95, at which time the spring 65 will act to complete the motion of the shield to the left, the stop 66 acting to arrest the shield in its neutral position, as shown in Figs. 5 and 6.

The fact that the counting mechanism releases 40 the shield before the lay reaches rear position permits the shield to move under and lift the pawl before the latter starts the forward stroke immediately following the advance movement of the slackener bar. A repeated large feed of 45 ratchet 70 at this time is therefore prevented, and there is no interference with the gradual return of the bar 19.

From the foregoing it will be seen that I have 50 provided means whereby a single actuator in the form of a pawl is rendered effective first to give the ratchet wheel a relatively large slackening stroke to advance the slackener bar, after which the same pawl effects a plurality of smaller step by step warp tightening movements of the 55 ratchet to return the slackener bar to its normal rear position. This control is exercised through a shield which is normally in position to prevent engagement of the pawl with the ratchet, but movable under influence of a counter surface to 60 a position which will permit the greater part of the stroke of the pawl to turn the ratchet. It will further be seen that on the next beat of the loom the counter mechanism releases the shield and the latter moves toward neutral position but 65 is restrained by a stop positioned by movement of the slackener bar away from rear position. This stop holds the shield in such position as to permit the step by step feeding of the ratchet until the bar approaches its rearmost position, at 70 which time lever 85 is rocked to remove the stop from the path of the shield and the latter returns to normal neutral position to hold the pawl idle with respect to the ratchet until another feeding movement of the slackener bar is indicated by 75 the counter mechanism.

Having thus described my invention it will be seen that changes and modifications may be made therein by those skilled in the art without departing from the spirit and scope of the invention and I do not wish to be limited to the 5 details herein disclosed, but what I claim is:

1. In a loom having a warp to be slackened, a slackener having warp slackening and return movement, a regulator for the slackener having two different motions the first of which occurs 10 when the slackener has a slackening movement and the second of which occurs when the slackener has a return movement, a single actuator means for the regulator, and a controller for the actuator means to render the latter effective to 15 give the regulator a relatively quick large motion when the slackener is to have a slackening movement and effective to give the regulator a gradual slower movement when the slackener is to have a return movement. 20

2. In a loom having a warp to be slackened, a slackener for the warp having slackening and return strokes, a regulator for the slackener to have one movement when the slackener is to have a slackening stroke and another movement 25 when the slackener is to have a return stroke, a single actuator for the regulator, and a controller for the actuator having two positions in one of which said controller renders the actuator operative to give the regulator a relatively quick 30 large movement when the slackener is to have a slackening stroke and the other position of the controller effective to cause the actuator to give the regulator a relatively slow movement when the slackener is to have a return stroke. 35

3. In a loom having a warp to be slackened, a slackener for the warp having warp slackening and return strokes, a regulator connected to and determining the motion of the slackener and having two different movements one of which occurs when the slackener is to have a slackening stroke and the other of which occurs when the slackener is to have a return stroke, an actuator to move the regulator, and a controller interposed 40 between the actuator and the regulator and capable of assuming two positions in one of which said controller renders the actuator effective to give the regulator a relatively quick large movement when the slackener is to have a slackening stroke and the other position of the controller 45 effective to render the actuator operative to give the regulator a gradual movement when the slackener is to have a return stroke. 50

4. In a loom having a warp to be slackened, a slackener for the warp having slackening and tightening strokes, a regulator connected to the slackener and determining the motion thereof, a ratchet moving with the regulator, a regularly moving pawl for the ratchet, and means to cause the pawl to give the ratchet and regulator a relatively large quick motion when the slackener is to have a slackening stroke and said means effective thereafter to cause the pawl to give a series of relatively short turning impulses to the ratchet and regulator when the slackener is to have a tightening stroke. 55

5. In a loom having a warp to be slackened, a slackener for the warp having slackening and tightening strokes, a regulator connected to and 60 determining the motion of the slackener and having slackening and tightening movements corresponding to the slackening and tightening strokes of the slackener, a ratchet moving with the regulator, a pawl to move the ratchet and 65

having a regular reciprocating motion, and a shield for the pawl to regulate engagement of the pawl with the ratchet, the shield when in one position rendering the pawl effective throughout the major part of its slackening stroke to actuate the regulator when the latter is to have a slackening stroke and said shield to have another position to render the pawl operative to give the ratchet and regulator a series of movements each occurring during a relatively small portion only of the slackening stroke of the pawl when a regulator and slackener are to have tightening strokes.

6. In a loom having a warp to be slackened, a lay, a slackener for the warp having slackening and tightening strokes, a regulator for the slackener, an actuator for the regulator operated by the lay and having a feeding stroke when the lay moves forwardly and a movable controller for the actuator and effective when in one position to render the actuator effective during a single forward motion of the lay to give the regulator a relatively large motion to give the slackener a slackening stroke and said controller when remaining in another position to thereafter render the actuator effective during each of a series of successive forward beats of the lay to give the regulator a gradual motion and give the slackener a gradual tightening stroke.

7. In a loom having a warp to be slackened, a lay, a slackener for the warp to have slackening and tightening strokes, a regulator connected to the slackener and determining the strokes thereof, a ratchet connected to the regulator, a pawl for the ratchet operated by the lay and having a slackening stroke when the lay moves forwardly, and a shield for the pawl, the shield in one position to render the pawl effective to give the regulator and slackener a relatively large motion during a single forward motion of the lay, and said shield when remaining in another position to render the pawl effective during but a small portion of each of a plurality of forward motions of the lay to actuate the regulator and cause the slackener to have a tightening stroke.

8. In a loom having a warp to be slackened,

a slackener to have slackening, tightening and idle periods, a single actuator to move the slackener during the slackening and tightening periods, counting mechanism, a controller for the actuator normally positioned to render the latter 5 inoperative with respect to the slackener during the idle period of said slackener, connections from the counting mechanism to move the controller from normal position and render the actuator effective to give the slackener a relatively 10 large slackening stroke, and means brought into action by the slackener to position the controller so as to render the actuator effective to give said slackener a series of relatively small strokes during the tightening period of said slackener. 15

9. In a loom having a warp to be slackened, a slackener having slackening, tightening and idle periods, an actuator for the slackener normally ineffective to move the latter during the idle periods thereof, counting mechanism, a controller for the actuator connected to and movable by the counting mechanism to render the actuator effective to give the slackener a relatively large motion during slackening periods thereof, and means moved by the slackener to 25 determine the position of the controller and hold the latter in position to render the actuator effective during the tightening period to give the slackener a series of short successive strokes.

10. In a loom having warp to be slackened, a slackener for the warp having slackening and tightening strokes, counting mechanism, a pawl having regular movements, control means for the slackener to be actuated by the pawl, a shield for the pawl normally positioned to render the 35 pawl ineffective to move the slackener, connections between the shield and counting mechanism to move the shield to a position to render the pawl effective to give the slackener a relatively large motion on the slackening stroke 40 thereof, and means operated by motion of the slackener on the slackening stroke thereof to hold the shield so that the pawl is effective to give the slackener a series of short successive motions during the tightening stroke thereof. 45

WALTER H. WAKEFIELD.
